PORTABLE WASH TUB AND WRINGER COMBINATION

Harold F. Brogdon, Grand Rapids, Mich., assignor, by mesne assignments, to Automatic Music, Inc., Grand Rapids, Mich., a corporation of Delaware

Filed June 9, 1958, Ser. No. 51,270

Term of patent 3½ years

Figure 1 is a front perspective view of a portable wash tub and wringer combination, showing my new design; and

I claim:

The ornamental design for a portable wash tub and wringer combination, as shown.
